UNITED STATES PATENT OFFICE.

LORENZO A. BONNET, OF CHICAGO HEIGHTS, ILLINOIS.

STOVE.

1,163,206.

Specification of Letters Patent.

Patented Dec. 7, 1915.

Application filed November 4, 1912. Serial No. 799,141.

To all whom it may concern:

Be it known that I, LORENZO A. BONNET, of Chicago Heights, in the county of Cook and State of Illinois, have invented certain new and useful Improvements in Stoves; and I do hereby declare the following to be a full, clear, and exact description of the invention, such as will enable others skilled in the art to which it appertains to make and use the same.

This invention relates to improvements in stoves and more particularly to cooking stoves adaptable for use with either solid or fluid fuel, the object of the invention being to provide means whereby a cooking stove is readily adapted to employ any kind of fuel; to obviate the necessity for removal of the fluid fuel burners when it is desired to use solid fuel; to so construct and arrange the fluid fuel burners and the ducts for conveying the fuel thereto, that these devices will not unduly obstruct the passage of heated air and products of combustion around the oven when solid fuel is employed, and to improve, simplify and reduce to a minimum the cost of construction of a cooking stove of the type stated, without detracting from the efficiency of the same.

With these and other objects in view, the invention consists in certain novel features of construction and combinations of parts as hereinafter set forth and pointed out in the claims.

In the accompanying drawings; Figure 1 is a perspective view partly broken away, showing my improvements; Fig. 2 is a sectional view, and Figs. 3, 4 and 5 are detail views.

1 represents a cooking stove provided with the usual fire box and with an elongated chimney flue chamber 2, between which and the back end of the top of the fire box a damper 3 is provided.

The oven 4 of the stove comprises side walls 5 and upper and lower plates 6 and 7, so disposed that the products of combustion from the fire box may be permitted to pass about the oven before reaching the flue chamber. To control the passage of products of combustion from the fire box through the space or chamber between the top oven plate and the stove top, a damper 8 is provided and a damper 9 may also be provided between said space or chamber and the fuel chamber 2.

The upper oven plate 6 is made with a plurality of ducts 10 fixed in said plate, preferably integral therewith and each of these ducts communicates at one end with a burner 11 which is also fixed in said oven plate preferably integral therewith and depressed somewhat below the upper face thereof, so as not to obstruct the draft and passage of products of combustion through the space between the upper oven plate and the stove top, when solid fuel is used in the fire box. The ducts 10 will be supplied with gas by means of any preferred pipe connections such as now commonly used with gas stoves. When the stove is used as a coal or wood stove, the burners 11 will be covered and protected by means of guard plates 12, which may be caused to rest upon seats 13 surrounding the burners, and these plates may be provided with sockets whereby they may be handled by means of an ordinary stove lid lifter.

Each burner is made with a central opening 13^a and air to support combustion is supplied to these openings by means of air ducts 14 formed on the bottom of the upper oven plate, said air ducts being open at the back of the stove.

When the stove is used as a gas stove, the various dampers will be closed and after removing the lids of the stove top, and the guard plates 12, sleeves or rings 15, having vent openings 16, will be placed upon the upper oven plate so as to surround the burners and serve to direct the flame and heat therefrom up through the usual stove top openings.

The lower oven plate 7 is made with a centrally located elongated depressed portion 17 having cast therein, a plurality of gas ducts, each of which is perforated to form burners 18. These ducts or burners will be connected with suitable pipe connections, such as commonly employed on gas stoves, to supply gas thereto. The burners 18 will be covered by means of a grating or open-work plate 19 which lies flush with the upper face of the lower oven plate 7.

Various slight changes might be made in the details of construction of my invention without departing from the spirit thereof or limiting its scope and hence I do not wish to restrict myself to the precise details herein set forth.

Having fully described my invention what

I claim as new and desire to secure by Letters Patent, is:—

1. In a stove of the character described, the combination with the stove body, of an oven provided with a plate having an integral burner depressed below the upper face thereof and having jet orifices arranged to discharge upwardly in the direction of the plane of the upper face of the oven plate, 10 said plate formed with an integral fuel duct communicating with said burner, and a removable cover plate for protecting said burner and adapted to have its upper surface in the plane of the upper face of the oven plate.
2. In a combined solid and fluid fuel stove, the combination with a body portion, a fire chamber, a stove top, and draft controlling means, of an oven in said body portion and 20 spaced therefrom and from the stove top, said oven having burners integral with its top plate and depressed below the top face of said plate, said integral burners having upwardly discharging jet orifices, and said top oven plate also having fuel ducts formed 25 therein, and means for protecting said burners without obstructing the space between the oven and the stove top, when the stove is used with solid fuel.
3. A stove provided with an oven having 30 a top plate formed with depressed burners integral therewith, removable guard plates for said burners when the latter are not in use and removable vented rings to surround said burners when the latter are in use. 35

In testimony whereof, I have signed this specification in the presence of two subscribing witnesses.

LORENZO A. BONNET.
